UNITED STATES PATENT OFFICE.

JOSEPH C. G. LIBERT, OF PARIS, FRANCE, ASSIGNOR TO THE ROXBURY CARPET COMPANY, OF BOSTON, MASSACHUSETTS.

DESIGN FOR CARPETS.

Specification forming part of Design No. 8,378, dated June 8, 1875; application filed May 17, 1875.
[Term of Patent 3½ years]

To all whom it may concern:

Be it known that I, JOSEPH C. G. LIBERT, of Paris, in the Department of Seine and Republic of France, have invented a new and original Design for Carpets, of which the following is a specification:

The nature of my design is fully represented in the accompanying photographic illustration.

I claim—

The design for carpets shown in the accompanying photographic illustration.

In testimony whereof I have signed my name to this specification in the presence of two subscribing witnesses,

JOSEPH C. G. LIBERT.

Witnesses:

M. COMTE,
E. PÉYIN.
